Primary Examiner — Freda S Nunn*(74) Attorney, Agent, or Firm* — LaRiviere, Grubman PC(57) **CLAIM**

The ornamental design for a housing for electric and electronic components, as shown and described.

DESCRIPTION

FIG. 1 is a front, top and left side perspective view of a housing for electric and electronic components showing our new design, the rear view being identical to that shown in FIG. 11;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a front, bottom and left side perspective view thereof;

FIG. 8 is a front, top and left side perspective view of a second embodiment thereof which is a mirror image of the housing shown in FIGS. 1-7;

FIG. 9 is a front, bottom and left side perspective view thereof as shown in FIG. 7;

FIG. 10 is a front perspective view thereof, which is a mirror image of the housing shown in FIGS. 1-9; and,

FIG. 11 is a rear view thereof.

The broken lines shown in the drawings are for environment only and form no part of the claimed design.
